REED ADJUSTMENT FOR LOOMS

Carl P. Bergstrom, Millbury, Mass., assignor to
Crompton & Knowles Loom Works, Worcester,
Mass., a corporation of Massachusetts

Application April 27, 1950, Serial No. 158,405

8 Claims. (Cl. 139—192)

1

This invention relates to improvements in the mounting of reeds in looms and it is the general object of the invention to provide a simple means by which the reed can be aligned with the shuttle boxes.

In a well-known type of loom for weaving terry fabrics the reed is carried by hanger means pivoted to the lay near the upper reed rib so that it can be swung backwardly and forwardly with respect to the lay incident to the terry forming operation. When the reed is moved to its forward position for guiding the shuttle during its flight the reed must be aligned with the backs of the shuttle boxes. In the past this alignment has been attained by several parts including an adjusting screw transverse of the lay or reed and a clamping screw parallel to the reed.

It is an important object of the present invention to provide a simple adjustment in the form of wedge to be located between the hand rail which engages the upper reed rib and the reed hanger pivoted on the lay. The wedge permits the use of a simple pivotal mounting for the hanger and also permits the upper end of the reed to be adjusted readily with respect to the hanger to align the reed with the shuttle boxes. When the desired adjustment has been made the several parts can be clamped together in adjusted position by a bolt extending preferably through the wedge.

While the wedge is of particular use in connection with swinging reeds of terry towel looms it may also be used for relative adjustment of the reed with respect to the lay in non-terry looms.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a diagrammatic front elevation of a loom lay having the invention applied thereto,

Fig. 2 is an enlarged vertical section on line 2—2, Fig. 1, showing the reed mounting at the left end as viewed in Fig. 1,

Fig. 3 is a detailed front elevation looking in the direction of arrow 3, Fig. 2,

Fig. 4 is a horizontal section on line 4—4, Fig. 3,

Fig. 5 is a detail plan view looking in the direction of arrow 5, Fig. 3, and

Fig. 6 is a diagrammatic view illustrating the manner in which the upper end of the reed may be adjusted with respect to the lay and the

2

hanger by movement of the wedge means to attain correct alignment with the shuttle boxes.

Referring particularly to Fig. 1, the lay L comprises a beam 1 and a single shuttle box 2 at the right end and a gang of shuttle boxes 3 at the left end. The lay beam is mounted on swords 4 and 5 which rock back and forth in the usual manner about a rocker shaft or pin not shown herein but well understood. 10 Right and left picker sticks 6 and 7, respectively, may be of usual construction for picking a shuttle S in active position back and forth across the lay. The reed R may be of usual construction and has top and bottom ribs 8 and 9, respectively. The reed has each end thereof mounted so that it can be swung relatively to the lay and since the end mountings are the same only one of them will be described in detail, namely, the mounting at the left end as viewed in Fig. 1.

Referring more particularly to Figs. 2—4, the sword 5 may be secured as at 10 to the beam 1 and has an upward extension 11 which is back of and extends above the shuttle race 12 on top 25 of the beam 1. A hanger support 13 is secured in fixed position on the lay by bolts 14 which extend through a vertical slot 15 in the sword extension 11. Support 13 may if desired have a forward flange or extension 16 to which a box mouth member 17 is secured at 18. Support 13 has horizontal slots 19 for bolts 14, and by reason of the slots 15 and 19 the support 13 can be adjusted vertically and horizontally on the lay. 30

A shuttle box guide plate 20 is secured to the lay sword as at 21 and has a groove 22 receiving a tongue 23 on the gang of shifting shuttle boxes 3. Each shuttle box will have a box back 24 along which the shuttle moves when being picked out of the box. This box back is aligned with the front face 25 of the guide plate 20 and the latter may be secured to the sword by the aforesaid bolt 10 in addition to bolt 21.

Extending forwardly from and integral with the support 13 at the right side of the latter is a bearing hub 26 which receives a pivot pin 27 substantially parallel to the lay beam and secured to the upper end of a reed hanger 28. The hanger extends downwardly from the pivot pin and has a horizontal part 29 which supports a back stay 30 grooved as at 31 to receive the lower rib 9 of the reed R. The rib 9 has a close fit with the groove 31 so that the lower end of the reed will move in unison back and forth with the backstay relatively to the lay beam. 50

Fig. 2 shows the means by which the reed

mounting can be manipulated for the formation of terry fabric. The lay end 35 which is secured to the beam 1 and sword 5 is provided with a back and forth adjustable but normally fixed pivot 36 on which is mounted a lever 37 the rear end of which, the right as viewed in Fig. 2, is connected to a tension spring 38 the lower end of which is attached in any approved manner to a fixed support (not shown). The forward arm 39 of lever 37 is pivoted as at 40 to a link 41 the forward end of which is pivoted as at 42 to the hanger 28. A positively controlled rod 43 is connected as at 44 to lever arm 39.

During each flight of the shuttle the reed R will be rearward of the fell of the cloth and in the position shown in Fig. 2 aligned with box back 24 to guide the shuttle. Assuming that the loom is at the start of a three pick terrying operation, the rod 43 will be drawn downwardly by well-known mechanism (not shown) for two successive forward beats of the lay so that the backstay 30 will be to the right of the position shown in Fig. 2 relative to the lay. On the third beat-up, however, the rod 43 will be in the position shown in Fig. 2 and as the lay approaches front center the reed will be in relative forward position to form the terry loops in well-known manner.

The upper rib 8 of the reed is received by a groove 50 in the under side of a hand rail 51, made preferably of wood, which extends across the lay above the shuttle race 12 and back stay. The rear side of the left end of the hand rail is formed with a flat downwardly and rearwardly inclined surface 52. A wedge means 53 has a front face 54 inclined similarly to surface 52 and has a rear flat surface 55 for engagement with a flat surface 56 formed on an extension or hand rail carrier 57 projecting laterally from the right of and integral with the hanger 28, as shown for instance in Fig. 3. The wedge means has a vertical slot 60 for a bolt 61 the forward part of which extends through the hand rail and the rear part of which after passing through the wedge member passes through a slot 62 extending vertically in the lateral extension 57. The bolt or securing means 61 may have a wing nut 63 threaded on the front end thereof and may have a holding nut 64 threaded on to the rear end thereof behind lateral extension 57.

When the reed is being assembled the bolt 61 will be loose so that the hand rail can be temporarily raised to permit fitting of the bottom rib 9 into the backstay groove 31. The hand rail 51 is then lowered until the top rib 8 of the reed is received snugly by the groove 50 in the under side of the hand rail. When the parts are in this position the hand rail will be supported by the reed and the latter will be supported by the back stay. The reed will be in its forward position relative to the lay at this time, as as shown in Fig. 2. The wedge means 53 will then be raised to the full line position of Fig. 6 to permit the upper rib of the reed to be rearward, or to the right in Fig. 2, of its desired position of alignment with the box back wall 24 and the nuts 63 and 64 will be given a preliminary setting. The wedge will then be pushed downwardly, as by a hammer, to some such position as shown in dotted lines, Fig. 6, until the upper end of the reed aligns with the shuttle box wall 24 and the face 25 of the guide 20, after which the nuts 63 and 64 will be tightened and the bolt 61 will be able to hold the hand rail, the wedge means 53, and the hanger 28 fixed together in relatively adjusted positions. After this adjustment is made the reed can swing rearwardly with respect to

the lay as already described for the formation of terry loops without disturbing the position of the wedge means or the parts in front of and behind it to which it is clamped by the bolt 61.

The reed mounting at the right end of the loom will be substantially the same as that already described in connection with Figs. 2-4, except that some of the parts will be of the opposite hand. The wedges at the two ends of the hand rail are alike and independently adjustable so that the right end of the reed can be adjusted relatively to the shuttle box 2 in a manner similar to the adjustment already described for the left end of the reed.

From the foregoing it will be seen that the upper end of the reed can be adjusted by very simple means with respect to the hanger 28 and the lay merely by changing the vertical position of the wedge 53. The bolt 61 holds the parts in any adjusted position so that once a correct adjustment has been made between the reed and the shuttle box the adjustment will be maintained. The adjusting wedge means 53 is much simpler than previously used means for effecting this adjustment, and the pivot pin 26 can remain in the same position with respect to the lay for all back and forth adjustments of the reed, since only the hand rail and not the hanger 28 is involved in reed adjustment. The reed rib 8 by reason of its close fit in the slot 50 moves in unison with the hand rail 51 in the back and forth adjustments of the latter effected by a change in the position of the wedge 53. The wedge will not ordinarily exert very much downward force, but if it exerts any such force it will in a direction to hold the rib 8 in close engagement with the hand rail. While the wedge has been described with more particular reference to adjustment of a reed in a terry loom, it will be understood that the wedge can also be used for attaining alignment of the reed with respect to the shuttle box in such looms as are not necessarily adapted for the weaving of terry fabrics.

Having thus described the invention it will be seen that changes and modifications of the foregoing specific disclosure may be made without departing from the spirit and scope of the invention.

What is claimed as new is:

1. In a loom lay having a shuttle race, a reed behind the race having the lower part thereof supported by the lay, a hand rail engaging the upper part of the reed and movable backwardly and forwardly therewith relatively to the lay, wedge means between the lay and hand rail mounted for vertical movement to vary the position of the hand rail and said upper part of the reed with respect to the lay, and means holding the hand rail and wedge means fixed in relative adjusted position with respect to the lay.
2. In a loom lay having a shuttle race, a lay sword having a part thereof extending upwardly from the shuttle race, a reed behind the shuttle race, a hand rail over the shuttle race engaging and movable with the upper part of the reed, wedge means between said part of the lay sword and the hand rail movable vertically with respect to the lay positioning the hand rail relatively to said part of the sword to effect a back and forth adjustment of the upper part of the reed, and means holding the hand rail and wedge means fixed in adjusted position with respect to said part of the lay sword.
3. In a loom lay having a shuttle race, a hand rail above the shuttle race having a surface inclined downwardly and rearwardly relatively to

the race, a reed extending between the lay and hand rail, the latter and the part of the reed in engagement therewith being movable in unison backwardly and forwardly relatively to the lay, wedge means having a downwardly and rearwardly engaging surface engaging said surface of the hand rail and having another surface oblique to said inclined surface and engaging a part of the lay and movable vertically relatively to the latter to change the position of the upper part of the reed with respect to the lay, and means holding the hand rail and wedge means fixed in adjusted position with respect to the lay.

4. In a loom lay having a shuttle race and a shuttle box, a hand rail above the shuttle race, means on the lay having a vertical surface, wedge means having a vertical surface engaging said surface of the lay and having another surface inclined downwardly and rearwardly, the hand rail having also a downwardly and rearwardly inclined surface engaging said other surface of the wedge means, a reed for the lay having part thereof engaging and moving backwardly and forwardly in unison with the hand rail relatively to the lay, said wedge means by downward movement relative to the lay effecting forward motion of the hand rail and said part of the reed with respect to the lay to adjust the reed relatively to the shuttle box, and means securing the hand rail and wedge means fixed in adjusted position on the lay.

5. In a loom lay having a sword and a shuttle box, a reed hanger pivotally mounted with respect to the sword, a back stay member supported by the hanger, a hand rail member above the back stay, a reed extending between said members and movable in unison therewith relatively to the lay, wedge means between the hanger and hand rail effective by a change of position thereof to vary the back and forth position of the hand rail and part of the reed engaged therewith relative to the shuttle box, and securing means holding the hanger, hand rail and wedge means in adjusted relative position.

6. In a terry loom having a lay provided with a shuttle box, a reed hanger, a pivotal connection between the lay and hanger around which the latter is swingable backwardly and forwardly relatively to the lay, a back stay member carried

by the hanger, a hand rail member above the back stay, a reed held by the members and movable in unison therewith around said pivotal connection, wedge means between the hanger and hand rail member movable relatively to the hanger and hand rail member to vary the position of the reed to align the latter with the shuttle box, and means extending through the wedge means holding the latter in fixed adjusted position relative to the hanger and hand rail member.

5 7. In a terry loom having a lay provided with a shuttle box, a reed hanger, a pivotal connection between the lay and hanger around which the latter is swingable backwardly and forwardly relatively to the lay, a back stay member carried by the hanger, a hand rail member above the back stay, a reed held by the members and movable in unison therewith around said pivotal connection, a hand rail carrier on the hanger, 15 wedge means between the hand rail member and carrier movable relatively to the carrier to vary the position of the reed to align the latter with the shuttle box, and means holding the carrier, hand rail member and wedge means in fixed adjusted position relative to each other.

20 8. In a loom lay provided with a shuttle box, a reed hanger pivotally mounted with respect to the lay, a back stay supported by the hanger, a hand rail above the back stay, a reed extending 25 between the back stay and hand rail the upper part of which is movable in unison back and forth with the hand rail relatively to the lay, wedge means between the hanger and hand rail effective by a change of position thereof relative to the hanger to vary the back and forth position of the hand rail and upper part of the reed with respect to the shuttle box, and securing means holding the hanger, hand rail and wedge means fixed to each other in relative adjusted position.
